UNITED STATES PATENT OFFICE

CHARLES AMÉDÉE CAMBAY, OF PARIS, FRANCE

AUTOMATIC COIN-CONTROLLED TELEPHONE APPARATUS

Application filed October 27, 1927, Serial No. 229,071, and in France November 4, 1926.

My invention relates to a self operating coin controlled apparatus for telephone calls of the kind in which the introduction of a coin or a counter in the apparatus frees a 5 movable hook on which hangs the telephone receiver and consequently allows a call to be made.

According to one mode of execution when the connection is made after a certain time, 10 sixty seconds for instance, said time being controllable, the coin falls in the apparatus. When the connection is delayed and when the call number is not free, the user may make a few calls and it will be necessary only for 15 him to hang again the receiver before the sixty seconds are up to get back his coin.

To this end the apparatus comprises besides the hook disengaging mechanism a balanced rocking device upon which the coin 20 falls momentarily and a liquid braking device in combination with the means which act upon the rocking device after the predetermined period allowed to make the connection, said rocking device oscillating to one side in the 25 proper direction to cause the falling of the coin inside the apparatus.

When the user has not been able to get the connection he puts back the receiver on the hook so as to lock the hook lever and at that 30 moment the liquid brake not having yet been able to act, a spring abutment carried by a slide actuated by the coming down of the hook lever causes the rocking device to move in the opposite direction and to eject the coin 35 out of the apparatus when it can be recovered by the user.

The mode of execution which has just been described comprises other details of construction concerning the hook locking device, a 40 key controlled mechanism to allow of unlocking the lever without necessitating the introduction of a coin, as well as other means hereinafter described.

45 The invention will be better understood by reference to the accompanying drawings and following specification in which:—

Figs. 1 and 2 show respectively by a front and side elevation a telephone combined with 50 a coin controlled apparatus.

Fig. 3 is a side elevation of the apparatus the closing plate being omitted.

Fig. 4 is a similar view showing the unlocking mechanism.

Fig. 5 represents the locking bolt for the 55 hook lever ready to be locked.

Figs. 6 and 7 show respectively two different positions of the balanced rocking device.

In the mode of construction shown in Figs. 1 to 7, the apparatus comprises a flat casing 60 1 fixed upon the side of the telephone 2 (Figs. 1 and 2) and provided with two openings 3 for the passage of the usual hook lever 4 to which the telephone properly so called 5 is suspended. 65

The apparatus comprises inside a groove 6 which guides the coin inserted at the top of the apparatus said coin on its travel acting upon the rocking lever 7. One tooth of the latter maintains the rocking lever 10 in engagement by means of its tooth 9, said lever being acted upon by a spring 11. This lever 10 is provided with a bent portion 10^a which constitutes a bolt placed above the lever 4 of the telephone 2 which is thus rendered 70 stationary in its inoperative position as long as a coin has not been introduced in the apparatus, an abutment 10^c limiting the movement of the lever 10. 75

As the coin falls in the groove 6 it must 80 first free the lever 4 when it is momentarily supported by two pins 12 carried upon a balanced rocking device 13 pivoted at 14 which as the case may be is moved either to the right of Fig. 6 so as to cause the coin 15 to fall in the apparatus, or to the left, Fig. 7, in order 85 to eject it as will be hereinafter described.

The hook lever 4 is engaged between two small plates 16^a secured to a part 16 provided with guiding slots 17 said part being 90 itself mounted in the upper part of the casing 1 and receiving its movement from the lever 4. On the other hand the part 16 is provided at the top with a lug 16^b acted upon by a spring shaft 18 designed to make the calls as 95 will be further explained and which is provided on the exterior with a knob 19^a. Said part 16 is also provided with a lug 16^c at its lower end having a pin 19 which constitutes 100 a guide and stop in the operative position for 100^a

a connecting rod 20 operated by the liquid braking device. The part 16 is also provided with a spring 21 for re-engaging the bolt 10^a upon the hook lever 4 in combination with a pin 10^b fixed upon the lever 10, and with another spring 22 for actuating the rocking device 13 by the intermediary of the pin 30 when the coin is to be ejected.

At the lower part of the casing 1 is arranged 10 a brake cylinder 23 filled with oil or any other liquid in which a small piston may move with circumferential play, said piston having the form of a cup provided with a hole closed by a ball 25 upon which bears a small spring 26.

15 The piston 24 is connected by a rod 27 to a lever 28 pivoted at 29 and pivotally connected at its other end with a connecting rod 20 which is guided by means of a slot 20^a upon the pin 19 of part 16; a return spring 32 is 20 designed to act upon the piston when the apparatus is set free, the pin 19 being drawn by the part 16 in its upward movement.

The connecting rod 20 is provided with an inclined extension 29^a which is designed to 25 act at the end of the movement of the piston 24 upon a pin 31 carried upon the balanced rocking device 13.

When the apparatus is disengaged the part 30 16 moves upwards and the spring 32 draws the piston 24 down in the liquid more or less rapidly so as to cause the link 20 to rise, the rapidity of this movement being a function of the play existing between the piston and the cylinder and of the position of the spring 35 32 upon the lever 28 which may be regulated at will by means of a screw 33; the downward movement of the piston may also be regulated by the height of the piston, by the tension of the spring or by these means combined together.

40 The disengagement of the lever 4 may be effected without introducing a coin, by means of a key inserted at 34 which raises a guided part provided with a lower extension 36 acting upon the extension 7^a of the unlocking lever 7, an appropriate device allowing the return of the part 35 to its position.

The coins are gathered in a collecting box 50 inside the apparatus and the coin when returned falls in a passage 6^a opening to the exterior.

The mode of operation of the apparatus is as follows:

The hook 4 being engaged the introduction 55 of a coin will therefore be sufficient to set it free said coin 15 falls in a chute 6 operating on its way the lever 7 which sets free the bolt 10^a and then comes temporarily to rest upon the pins 12 of the balanced rocking device 13, 60 as will be seen in Fig. 4, the bolt 10^a being in the position shown in Fig. 5.

The telephone being now taken from the hook the lever 4 moves upwards taking with it the plate 16 when a subscriber may then 65 be called. When the part 16 rises the lever

20 is disengaged from the pin 19 and the spring 32 acting upon the lever 28 causes the piston 24 to go down in the cylinder 23 containing a certain quantity of liquid which must pass from one side of the piston to the other in a predetermined time, sixty seconds for example, the valve 25 being kept upon its seat; if the connection is made before the sixty seconds are up when the piston is at the end of its downward movement, that is to say that at the expiration of the time the extension 29^a engages the pin 31 and causes the rocking device 13 to come in the position shown in Fig. 6 when it ejects the falling coin in the receptacle 37 which is placed inside the apparatus.

At the end of the conversation the telephone 5 is put back the plate 16 is consequently brought down compelling the spring 21 to act upon the pin 10^b to engage again the lever 4. The downward movement of the pin 19 brings down again the connecting rod 20 with the effect of actuating the lever 28 and raising the piston 24 to its inoperative position, the liquid in the cylinder 23 ascending without difficulty, the valve being open during this ascending movement.

If the connection has not been made within the major portion of the time allotted for making the connection, say two-thirds of the time assumed, or forty seconds, the button 19^a is depressed moving the slide 16 down to oscillate the hook 4 and cause the supervisory signal at the central station to flash, to call the attention of the central operator.

The distance between the button 19^a and the top of the case is chosen less than the full movement of the slide 16, so that the springs 21 and 22 will not operate on their respective pins 10^b and 30, hence this operation may be repeated several times before full movement of the lever 28 has been attained, as this lever is partially returned to initial position each time the button 19^a is manipulated. If no connection is obtained the hook 110 is hung up and the coin returned.

To ascertain when the forty seconds has expired, the rod 27 may be provided with an indicator showing through a window in the casing or otherwise.

In the case of the lever being disengaged by the introduction of a coin in the apparatus, the call is not answered even after pressing several times upon the push button 19^a or when the number called up is not free, the hook lever must again be locked before the sixty seconds are up by putting the receiver back in order to recover the coin. In fact in that case the piston 24 has not had sufficient time to come to the end of its downward movement in order to engage the inclined surface 29^a with the pin 31, the pin 30 of the rocking device being then actuated by the spring 22 as will be seen in Fig. 7, so as to cause the coin 15 which takes its position 130

at 6^a to fall outside the apparatus where it may be recovered by the user.

What I claim and desire to secure by Letters Patent of the United States is:

5 1. In a pay attachment for telephones having a receiver supporting hook; a coin chute, a lever having one end projecting into said chute and operated by a coin, a pivoted, 70 spring-retracted locking bolt for engaging said hook and held and released by said lever, a pivoted temporary coin receiver in the chute below the aforesaid lever, two actuating pins on the receiver, a part for connection to and movable with the hook, means 75 on said part to engage one of the pins and tilt the coin receiver in one direction, and timing means operated to tilt said receiver in the opposite direction after the hook has been raised, and means on said part to return the locking bolt to locking position when the hook is lowered.

2. In a pay mechanism for telephones having a receiver supporting hook; a coin chute, a pivoted lever having one end in the chute to be actuated by a coin passing therethrough, a locking bolt to normally hold the hook depressed and so held by said lever, a pivoted temporary coin receiver in said chute below said lever, two actuating pins on the receiver, a liquid timing device comprising a liquid containing cylinder, a piston therein, means to displace the piston in the cylinder, means to permit said piston to move rapidly in one direction and slowly in the opposite direction, a second lever having one end connected to the piston, a vertically movable slotted element connected to the other end of the second lever and arranged to contact with one of said pins to tilt the receiver for retention of a coin therein at the end of the piston movement, a movable part for connection to the telephone hook, a pin thereon entering the slot in the element to hold the element depressed, means on the part to engage the other pin on the receiver to tilt it to return the coin to the operator before completion of the piston movement, a pin on the bolt and means on the part to return it to locking position when the part is depressed for engagement by 50 said first lever.

3. In a pay telephone, the combination with a telephone including its hook and receiver: of a latch for the hook, a coin chute, a control member for the latch projecting into the chute and operated by a coin to release the latch, a part movable in unison with the hook, means on said part to move the latch into latching position when the receiver is placed on the hook, a pivoted member to temporarily receive the coin, timing mechanism to tilt the pivoted member to discharge it for retention of the coin and means on said part to tilt the pivoted member to return the coin before the timing mechanism has actuated the pivoted member.

4. In a pay telephone, the combination with a telephone including its hook and receiver; of a latch for the hook, a coin chute, a control member for the latch projecting into the chute and operated by a coin to release the latch, a part movable in unison with the hook, means on said part to move the latch into latching position when the receiver is placed on the hook, a pivoted member to temporarily receive the coin, timing mechanism to tilt the pivoted member to discharge it for retention of the coin, means on said part to tilt the pivoted member to return the coin before the timing mechanism has actuated the pivoted member, and manual means to reciprocate said part and hook to signal the central operator before the discharge of the coin from said pivoted member.

5. In a pay telephone, the combination with a telephone including its hook and receiver; of a latch for the hook, a coin chute, a control member for the latch projecting into the chute and operated by a coin to release the latch, means on said part to cause the latch to engage the hook when the receiver is placed thereon, a temporary coin receiver onto which the chute discharges a coin, timed mechanism to discharge the coin from said receiver for retention and means on the part to discharge the coin for return before the time mechanism has operated to retain the coin.

In testimony that I claim the foregoing as my invention, I have signed my name.
